UNITED STATES PATENT OFFICE.

DE WITT CLINTON PRESCOTT, OF MARINETTE, WISCONSIN.

SAW-MILL CARRIAGE.

SPECIFICATION forming part of Letters Patent No. 376,678, dated January 17, 1888.

Application filed June 9, 1887. Serial No. 240,834. (No model.)

To all whom it may concern:

Be it known that I, DE WITT CLINTON PRESCOTT, a citizen of the United States, residing at Marinette, in the county of Marinette and State of Wisconsin, have invented a certain new and useful Improvement in Saw-Mill Carriages, which is fully set forth in the following specification, reference being had to the accompanying drawings, in which—

10 Figure 1 is a plan view of a saw-mill carriage embodying my invention; Fig. 2, a side elevation of the same; Fig. 3, a detail sectional view taken on the line 1 1 of Fig. 1; Fig. 4, a detail sectional view taken on the line 2 2 of Fig. 1; Fig. 5, a detail plan section taken on the line 3 3 of Fig. 4; Fig. 6, a detail view of the friction-band mechanism; Fig. 7, a detail sectional view of the cam-shifting device detached, taken on a line corresponding to the line 4 4 of Fig. 5; and Fig. 8, a detail sectional view of the same, taken on the line 5 5 of Fig. 7. Figs. 1 and 2 are on the same scale. Figs. 3 to 8, inclusive, are on the same scale with respect to each other, but on an enlarged scale 25 with respect to Figs. 1 and 2.

Like letters refer to like parts in all the figures of the drawings.

My invention relates to saw-mill carriages, and more particularly to that class in which 30 the carriage is provided with automatic means for shifting the log clear of the saw upon its return movement and advancing the same to its original position upon its forward movement, and it has for its object to provide a 35 simple and efficient construction for positively effecting these results; and to this end my invention consists in certain novel features, which I will now proceed to describe, and will then particularly point out in the claims.

40 In the drawings, A represents the frame of the saw-mill carriage, this frame being of any approved construction and provided with the usual means for securing the log in position thereon. This frame is mounted on a series

45 of trucks composed of axles B, provided with wheels b and b', secured to said axles and revolving therewith. These wheels travel upon the rails C and C', the said wheels and rails being constructed in any approved form, al- 50 though I prefer that shown, in which one of the rails, as C', is provided with a projecting rib, while the corresponding wheel, b', is grooved

to fit upon the rib and prevent lateral displacement of the trucks.

The carriage A is free to move laterally 55 upon the axles B, so as to clear the log of the saw upon the return movement of the carriage and allow it to be moved up into position again upon the forward movement, and it is to the means for effecting this lateral move- 60 ment of the carriage that my present invention more particularly relates. Upon one or more of the axles B is secured a friction-wheel, D, which revolves with the said axle.

D' represents a friction band or ring sur- 65 rounding the friction-wheel D, the said band being split or divided, as shown at d, and provided with an adjusting bolt or screw, d', by means of which it may be tightened or loosened, as desired. The said friction-band is 70 preferably provided with an inner facing, d'', of vulcanized fiber or other suitable material, and has upon its outer periphery a projecting lug, D'', in the path of which are arranged stops or buffers to limit its travel. These 75 stops or buffers are preferably constructed as follows:

E represents a plate secured to the frame A and carrying boxes E' and E'', arranged on each side of the friction-band D'. Within suitable 80 recesses in the boxes E' and E'' are arranged blocks of rubber, e' and e'', which may be ad- justed to project to a greater or less extent, as desired, by means of adjusting-screws e, passing through the boxes and bearing against 85 their inner ends. This friction-band device, although of my invention, is not claimed by me specifically in the present application, as it forms the subject-matter of claims presented in another application filed by me August 2, 90 1886, Serial No. 209,799. I have shown and described them in the present instance as the form of actuating mechanism for my shifting device which I prefer to employ; but I do not limit myself to this particular actuating mech- 95

In the construction shown two of the axles B are shown provided with these friction- bands, and each friction-band is provided with a crank-pin, D³, a connecting-rod, D⁴, being 100 employed to connect the two friction-bands together. It is obvious that only a single band may be employed, if desired, or that a greater number than two may be used. These fric-

tion-bands serve, by means of pitmen D⁵, to operate the cam-shifting devices for giving to the saw-mill carriage a lateral movement upon the axles B. In the present instance I have 5 shown two of these cam-shifting devices as employed, one being arranged near each end of the carriage, although it is of course obvious that a greater or less number may be used, if desired. The two shifting devices being identical in their construction, I will describe only one of them, it being of course understood that the same description is equally applicable to the other. The end axle, B, is provided with fixed collars b², between which is arranged 15 a sleeve, F, mounted loosely on the shaft, so as to be capable of a rocking or oscillating movement around the same, the collars b² preventing any lateral movement of the said sleeve. An arm, f, extends downward from 20 the said sleeve and has connected to its lower end the pitman D⁵ by means of a bolt or pin, f', passing through a suitable boss or hub, F', on the lower end of the arm f.

On its upper side the sleeve F is provided 25 with a cam-groove, F², which is suitably inclined with relation to the axis of the sleeve F, and consequently to the direction of motion of the entire carriage. This cam-groove F² is preferably formed by means of parallel inclined projections F³, which co-operate with a suitable fixed projection on the frame A, which projection enters the groove F² between the cam projections F³, so that when the sleeve F is oscillated or vibrated a lateral movement 30 will be imparted to the frame. In its preferred form this projection consists of a roller, G, mounted on a suitable axis or support, g, carried by a transverse beam, G', attached to the frame A or forming a portion of the said 35 framing.

The cam projections F³ are provided with bearing-surfaces f³, of steel or anti-friction metal, against which the roller G may act, and these surfaces are detachable for the purpose 40 of renewal or repair, being secured to the projections by bolts f², or in any other suitable manner.

In order to properly lubricate the sleeve F, I provide within the walls of the same oil-chambers H, (shown more particularly in 45 Figs. 7 and 8 of the drawings,) the said oil-chambers being provided with filling-passages h and with lubricating-passages h', leading to the bearing-surface of the sleeve F.

50 I will now proceed to describe the operation of my improved saw-mill carriage, premising that the operation of the friction devices is the same as that described in my other application hereinbefore specified, and therefore 55 needs no extended description here. The parts having been properly adjusted, the carriage will start upon its forward travel to make the first cut, when the friction-bands will, through the operation of the pitmen D⁵, 60 impart a rotary motion to the sleeves F, causing the same to make a partial rotation around the axles B, on which they are mounted, and,

through the medium of the cam-grooves F², formed by the cam projections F³, to impart a lateral movement to the frame A upon the 70 axles B, this lateral movement being sufficient to present the log to the saw in proper position to make the first cut. When the carriage has completed its forward journey and the direction of its travel is reversed, the friction-bands will, through the medium of the pitmen D⁵, impart a partial movement of rotation to the sleeves F, and will move the frame A bodily 75 upon the axles away from the saw, thereby carrying the log from the saw and preventing 80 any contact between the two during the return movement of the carriage.

It will be seen that the cam-shifting device described provides a simple and efficient means for shifting the carriage laterally, it being of 85 such a nature that it operates positively and quickly, while all the parts are opened to inspection and may be readily cleaned or repaired when necessary. The first cost is slight, and the mechanism, not being delicate, is not 90 liable to get out of order.

It will of course be understood that various modifications may be made without departing from the principle of my invention. For instance, although I prefer to employ the connecting-rod D⁴ between the friction-bands, in order to insure simultaneous operation of the two, still this rod may be dispensed with. Moreover, although I have shown the cam-shifting devices as mounted directly upon the 95 axles, they might be supported from these axles in any suitable manner for effecting their purpose. I therefore do not wish to be understood as limiting myself strictly to the precise details of construction hereinbefore set 100 forth, and shown in the drawings.

Having thus described my invention, what I claim as new, and desire to secure by Letters Patent, is—

1. In a saw-mill carriage, the combination, 110 with the truck-axles, of the carriage-frame capable of lateral movement on the axles, one or more cam-shifting devices mounted on the said axles, capable of a limited oscillation thereon, and each consisting of a sleeve provided with a cam-groove, a suitable fixed projection from the carriage-frame to enter said groove, and mechanism for partially rotating or oscillating the said cam-shifting devices in each direction to shift the carriage, substantially as and for the purposes specified. 115

2. In a saw-mill carriage, the combination, with the truck-axles, of the carriage-frame capable of lateral movement on the axles, cam-shifting devices supported on the axles and 120 each provided with a cam-groove, corresponding projections on the carriage to enter the said grooves, and actuating mechanism connecting the cam-shifting devices and one or more of the axles, substantially as and for the purposes 125 specified.

3. In a saw-mill carriage, the combination, with the truck-axles, of the carriage-frame capable of lateral movement on the axles, the

cam-shifting devices mounted on one or more of the axles and each provided with a cam-groove, a corresponding projection on the carriage-frame, and friction-wheels mounted on 5 one or more of the axles and each provided with a friction-band connected to the cam-shifting devices to operate the same, substantially as and for the purposes specified.

4. In a saw-mill carriage, the combination, 10 with the truck-axles B, of the carriage-frame A, capable of lateral movement on said axles, the sleeves F, mounted on the axles B between fixed collars b^2 and provided with inclined projections F^3 , forming the cam-groove F^2 , the 15 projection G of the carriage-frame, the friction-wheels D, having friction-bands D', and the connecting-rod D ^{4} and pitmen D ^{5} , substantially as and for the purposes specified.

5. In a saw-mill carriage, the combination, 20 with the truck-axle B, having fixed collars b^2 , of the sleeve F, mounted on said axle between the said collars, and provided with the inclined projections F^3 , forming the cam-groove F^2 , and the carriage-frame A, capable of lateral movement 25 on the said axle and provided with the roller G, arranged between the projections F^3 , substantially as and for the purposes specified.

6. In a saw-mill carriage, the combination, with the axle B, of the carriage-frame A, capable of lateral movement thereon, the roller G, 30 mounted on a projection from said frame, the sleeve F, mounted on the axle and provided with cam projections F^3 , arranged to embrace said roller, and separate bearing-pieces f^3 for the roller, detachably secured to the projections F^3 , substantially as and for the purposes 35 specified.

7. In a saw-mill carriage, the combination, with the axle B, of the sleeve F, mounted thereon and provided with cam projections to 40 operate the carriage-frame, said sleeve being provided with oil-chambers H on each side thereof, having filling-apertures h and lubricating-passages h', and the carriage-frame provided with a projection engaging with the cams 45 of said sleeve, substantially as and for the purposes specified.
